LINK CHAIN FOR A BRACELET OR SIMILAR ARTICLE

Michael Chernow, New York, N. Y.

Application November 13, 1953, Serial No. 27,596

Term of patent 14 years

(Cl. D15—4)

To all whom it may concern:

Be it known that I, Michael Chernow, a citizen of the United States and residing at New York, in the county of New York and State of New York, have invented a new, original, and ornamental Design for a Link Chain for a Bracelet or Similar Article, of which the following is a specification, reference being had to the accompanying drawing, forming part thereof, and in which

Fig. 1 is a top plan view of a link chain for a bracelet or similar article, showing my new design with the links shown in full lines being repeated throughout the length of the chain as shown in dotted lines,

Fig. 2 is a side elevational view thereof,

Fig. 3 is a top plan view of one of the links of the link chain on a greatly enlarged scale, and Fig. 4 is a sectional view taken along the line 4—4 of Fig. 3.

I claim:

The ornamental design for a link chain for a bracelet or similar article, substantially as shown and described.

MICHAEL CHERNOW.
